AUTOMATIC WEDGE TO ADJUST SLACK BETWEEN BUFFER ON ENGINE AND TENDER

Filed Feb. 13, 1929

Fig. 1.

UNITED STATES PATENT OFFICE

HAROLD MARTININSON LUND, OF DILWORTH, MINNESOTA

AUTOMATIC WEDGE TO ADJUST SLACK BETWEEN BUFFER ON ENGINE AND TENDER

Application filed February 13, 1929. Serial No. 339,712.

This invention relates to locomotive buffers, and more particularly to means for automatically maintaining the buffer plates of a device of this character in proper frictional relation.

At the present time, there are two types of locomotive buffers in use, one of these types employing springs arranged rearwardly of the adjustable chafing plate for maintaining the latter in engagement with the floating chafing block. The other type of buffer is provided with an adjustable chafing plate having an inclined rear face adapted to be engaged by an adjustable wedge for maintaining it in frictional engagement with the chafing block.

Both of the above referred to types of buffers have been found to possess disadvantages, since it is necessary for the proper operation of these devices, that the frictional engaging faces contact with each other at substantially the proper pressure. The spring pressed devices have been found to provide insufficient pressure for accomplishing the purpose, while the wedge actuated chafing plates have been found to exert either too slight or too great a pressure against the chafing plate.

An important object of the present invention is to provide novel means for maintaining proper frictional contact between the buffer members without causing undue strain on the draw bar, such as occurs through the use of the ordinary wedge operating chafing plates when the wedges are too tightly adjusted.

A further object is to provide novel means for maintaining the proper frictional engagement whereby the engine is caused to ride smoother and steadier at high rates of speed and wherein the engine is prevented from rocking, particularly when passing around curves during which the rocking action usually is particularly noticeable.

45 A further object is to provide a device of

the above mentioned character which is automatically self adjusting as wear takes place between the parts.

A further object is to provide novel means for resiliently adjusting the tension between 50 the buffer parts to secure the correct frictional engagement therebetween.

Other objects and advantages of the invention will become apparent during the course of the following description.

In the drawings I have shown several embodiments of the invention. In this showing,

Figure 1 is a fragmentary plan view,

Figure 2 is a section on line 2—2 of Figure 1,

Figure 3 is a detail perspective view of the wedge and associated elements,

Figure 4 is a fragmentary perspective view of one end of the wedge.

Figure 5 is a plan view of a modified form of the device, and,

Figure 6 is a detail section on line 6—6 of Figure 5.

Referring to the drawings, the numeral 10 designates the rear portion of an engine to which a stationary chafing plate 11 is secured by bolts 12 or other fastening elements. The chafing plate is provided with a curved inner face 13, as shown in Figure 1 and a curved 75 flange 14 projects upwardly beyond the top of the plate. A floating chafing block 15 is arranged against the curved face of the plate 11 and the forward face of the block 15 is curved to conform to the shape of the rear face 80 of the plate 11. The block 15 is provided at its central top portion with a forwardly extending lug 16 having a downwardly turned lip 17 extending over the flange 14 to support the chafing block 15 in position. The 85 rear face 18 of the block 15 also is curved as indicated in Figure 1, for a purpose to be described.

A chafing plate pocket 19 is carried by a buffer plate 20 which is arranged against 90

the forward end of the locomotive tender and is secured thereto by suitable fastening elements (not shown) passing through outstanding flanges 21 formed integral with the plate 20. The pocket 19 is provided with top and bottom walls 22 and a rear wall 23.

An adjustable chafing plate 24 is mounted in the pocket 19 and is provided with a curved forward face 25 corresponding in shape to and adapted to engage the curved face 18 of the floating block 15. The rear face of the plate 24 is tapered as at 26 for a purpose to be described, and is spaced a substantial distance from the forward face of the rear wall 23 of the pocket. The chafing plate 24 is provided at its top and bottom, substantially centrally thereof, with lugs 27 forming channels 28 for a purpose to be described.

The pocket 19 is provided in opposite sides with openings 29 and 30 through which a wedge 31 is adapted to extend. This wedge corresponds generally in shape to the wedges usually employed in devices of this character, it being tapered whereby its rear face 32 is adapted to contact with the forward face of the wall 23, while its forward face 33 contacts with the tapered face 26 of the plate 24. The wedge is provided with upper and lower longitudinal flanges 34 which are slidable in the channels 28 previously described.

The wedge is provided at one end with a block portion 35, and from this block portion to the opposite end of the wedge a groove 36 is formed for a purpose to be described. At the narrow end of the wedge, the groove 36 extends entirely through the wedge as at 37, for a purpose to be described.

A rod 38 is arranged in the groove 36 and extends through a suitable opening formed in the block portion 35 of the wedge. This rod is provided at one end with a transverse head 39 which is slidable into the cut out portion 37. The opposite end of the rod is threaded for reception within the nuts 40, and a washer 41 is arranged against the innermost nut. A similar washer 42 is arranged against the adjacent end of the block portion 35, and a relatively strong compression spring 43 contacts at its ends with the washers 41 and 42. Thus it will be apparent that the head 39 is normally urged inwardly toward the opening 30.

The form of the invention previously described is adapted to be employed in connection with adjustable chafing plates having tapered rear faces. In another form of buffering devices in common use, the rear face of the adjustable plate is formed parallel to the inner wall of the pocket, and springs are arranged in the pocket for normally urging the adjustable plate forwardly into engagement with the floating block 15. The form of the invention illustrated in Figures 5 and 6 is adapted to be employed in place of the springs

usually used in the construction referred to. The wedge member employed in the modified form of the device is identical with that previously described and need not be referred to in detail.

Referring to Figures 5 and 6, the numeral 44 designates a stationary wedge adapted to be arranged in the pocket 19 when the device is used in connection with an adjustable chafing plate having its rear face parallel to the inner face of the pocket. The stationary wedge is provided with front and rear faces 45 and 46 which are tapered with respect to each other, and the smaller end of the stationary wedge is provided with a rearwardly turned lip or flange 47, which is adapted to engage the outer wall of the pocket 19. When this form of the device is employed, it will be apparent that the front wall 33 of the wedge 31 is parallel to the rear face 46 of the stationary wedge 44.

Since the space between the rear wall of the adjustable buffer plate and the inner wall of the pocket varies with different constructions, means is provided for adjusting the distance between the forward face of the wedge 31 and the rear face of the wedge 44. As shown in Figures 5 and 6, a flat liner 48 may be arranged between the adjacent faces of the two wedge members, and is provided at one end with a lip portion 49 adapted to contact with the adjacent end of the stationary wedge 44.

The operation of the form of the device shown in Figures 1 to 4 inclusive is as follows:

The head 39 of the rod 38 is pulled outwardly beyond the end of the wedge, against the tension of the spring 43, and is turned at right angles to the position shown in Figure 3, whereby it contacts with the end of the wedge. The wedge is then inserted into the pocket and placed in the position shown in Figure 1, whereupon the head 39 is turned to the position shown in Figure 3. The spring 43 will then act to draw the head 39 into engagement with the adjacent outer wall of the pocket 19, and the wedge 31 will be urged inwardly tending to thrust the chafing plate forwardly into firm frictional engagement with the rear face 18 of the floating block 15.

The wedge obviously will be maintained in proper position with respect to the plate 24 by the engagement of the wedge in the openings 29 and 30 of the pocket, and by engagement of the flanges 34 with the channels 28. As wear takes place, it will be apparent that the spring 43 will compensate therefor by gradually moving the wedge inwardly. The arrangement of the head 39 within the cut out portion 37 permits such inward movement of the wedge to take place.

It will be apparent that the pressure exerted against the block 15 by the plate 24 will

depend upon the tension of the spring 43. The tension of this spring is relatively strong, and readily may be adjusted by changing the position of the nuts 40 on the rod 38.

- 5 The operation of the form of the device shown in Figures 5 and 6 is substantially the same as in the form previously described. The forward face 45 of the stationary wedge 44 forms the necessary inclination with respect to the rear face of the adjustable chafing plate in connection with which this form of the invention is employed, whereby inward movement of the wedge is adapted to effect the proper frictional engagement between the 15 adjustable chafing plate and the floating block 15. The liner 48 may be omitted when the space between the faces 43 and 46 of the two wedges is sufficient to fill the space between the rear face of the adjustable chafing plate and the inner wall of the pocket.

It will be apparent that a much finer adjustment of the wedge can be obtained than with the present forms of wedges wherein openings are provided in the wedge at spaced 25 intervals to receive a locking pin. Thus, any predetermined pressure may be obtained to cause the buffering device to operate properly, and the locomotive thus will ride smoother than with the present constructions, and 30 rocking of the locomotive will be eliminated, particularly when passing around curves.

The device also eliminates the rearward movement of the adjustable plate 24 which occurs when springs are used rearwardly 35 thereof for maintaining the plate in engagement with the rear face of the block 15. The inclination of the contacting faces of the wedge and the plate 24 is such that rearward movement of the engine with respect to the 40 tender will not displace the wedge transversely of the pocket, and accordingly rearward movement of the plate 24, which takes place when the usual spring constructions are employed, is eliminated.

45 The device not only causes the buffer to operate in the manner described, but it also eliminates damage to draw bars connecting the engine and tender, which sometimes occurs when the usual wedge constructions are employed and the wedges are too tightly inserted.

It is to be understood that the forms of the invention herewith shown and described are to be taken as preferred examples of the 55 same and that various changes in the shape, size and arrangement of parts may be resorted to without departing from the spirit of the invention or the scope of the subjoined claims.

60 I claim:

1. In a locomotive buffer, the combination with a pair of frictionally engaging chafing elements, and a pocket for one of said elements, said last named element having a 65 tapered face of a wedge extending trans-

versely of said pocket and having a tapered face engaging the tapered face of said last named chafing element, a rod slidable with respect to said wedge and having a portion at one end thereof engaging said pocket, and a spring mounted between the other end portion of said rod and said wedge and adapted to move the latter to increase the pressure thereof against the other of said chafing elements. 70

1.2. In a locomotive buffer, the combination with a pair of frictionally engaging chafing elements, and a pocket having an opening in its outer portion for the reception of one of said elements, said last named element having a tapered inner face said pocket having openings in opposite walls thereof, a wedge extending through said last named openings and tapered to engage the inner face of the chafing element arranged in said pocket, a rod slidably mounted in said wedge and extending longitudinally with respect thereto, one end of said rod extending through one of the last named openings in said pocket and provided with a head engaging against the outer face thereof, and a spring surrounding the opposite end of said rod and contacting with said wedge to urge it to move laterally in said pocket to increase the pressure between said chafing elements. 85

3. In a locomotive buffer, the combination with a pair of frictionally engaging chafing elements, and a pocket having an opening in its outer portion for the reception of one of said elements, said pocket having openings in opposite walls thereof, a wedge extending through said last named openings and engaging the inner face of the chafing element arranged in said pocket, a rod slidably mounted in said wedge and extending longitudinally with respect thereto, one end of said rod extending through one of the last named openings in said pocket and being provided with a head engaging against the outer face thereof, and a spring surrounding the opposite end of said rod and contacting with said wedge to urge it to move laterally in said pocket to increase the pressure between said chafing element, said head being movable to one position to engage said pocket and to another position to permit its removal from said pocket together with said wedge. 100

4. In a locomotive buffer, the combination with a pair of frictionally engaging chafing elements, and a pocket having an opening in its outer portion for the reception of one of said elements, said pocket having openings in opposite walls thereof, a wedge extending through said last named openings and engaging the inner face of the chafing element arranged in said pocket, a rod slidably mounted in said wedge and extending longitudinally with respect thereto, one end of said rod extending through one of the last 105 110 115 120 125 130

named openings in said pocket and being provided with a head engaging against the outer face thereof, and a spring surrounding the opposite end of said rod and contacting with said wedge to urge it to move laterally in said pocket to increase the pressure between said chafing element, said wedge being provided in the end thereof adjacent said head with a slot normally receiving said head to maintain it in engagement with said pocket, said rod being slidable to disengage said head from said slot whereby it may be turned to a second position to permit its removal from said pocket together with said wedge.

15 In testimony whereof I affix my signature.
